UNITED STATES PATENT OFFICE.

ALBERT BROD, OF NEW YORK, N. Y.

DESIGN FOR A RING OR SIMILAR ARTICLE.

Application filed December 2, 1924. Serial No. 11,566. Term of patent $3\frac{1}{2}$ years.

To all whom it may concern:

Be it known that I, ALBERT BROD, a citizen of the United States of America, residing at New York city, county and State of New York, have invented a new, original, and ornamental Design for a Ring or Similar Article, of which the following is a specification, reference being had to the accompanying drawing, forming part hereof, in which—

Fig. 1 is a side view of a ring showing my new design, and Fig. 2 is an edge view thereof.

I claim:

The ornamental design for a ring or similar article as shown.

Signed at Newark, N. J., this 26th day of November, 1924.

ALBERT BROD.
